The ornamental design for a makeup brush, as shown and described.

DESCRIPTION

FIG. 1 is a perspective view of a makeup brush, showing my new design;

FIG. 2 is a left side view of the makeup brush shown in FIG. 1;

FIG. 3 is a right side view of the makeup brush shown in FIG. 1;

FIG. 4 is a front side view of the makeup brush shown in FIG. 1;

FIG. 5 is a rear side view of the makeup brush shown in FIG. 1;

FIG. 6 is a bottom view of the makeup brush shown in FIG. 1; and,

FIG. 7 is a top view of the makeup brush shown in FIG. 1. The broken lines shown are included for the purpose of illustrating portions of the makeup brush that form no part of the claim.
